UNITED STATES PATENT OFFICE.

FRITZ FINCKH, OF ESSEN, GERMANY, ASSIGNOR TO FRIED. KRUPP AKTIENGESELLSCHAFT, OF ESSEN-ON-THE-RUHR, GERMANY.

SELF-DUMPING VEHICLE.

1,427,451.

Specification of Letters Patent. Patented Aug. 29, 1922.

Application filed December 3, 1920. Serial No. 428,112.

To all whom it may concern:

Be it known that I, FRITZ FINCKH, residing at Essen, Germany, a citizen of the German Republic, have invented a certain 5 new and useful Improvement in Self-Dumping Vehicles, of which the following is a specification.

This invention relates to self-discharging vehicles discharging from the bottom, and 10 has for its special object, by establishing a joint connection between the bottom doors which are adapted to be automatically opened by the weight of the lading and the outer walls, which serve to confine the loading 15 space and immediately adjoin the respective outer end portions of said doors, to cause these outer walls to move conjointly with the doors and thereby to secure a breaking up of the lading, further the quick formation 20 of steep chutes, and lastly the provision of a large discharge opening.

One embodiment of the subject matter of my invention is illustrated in the accompanying drawing, showing a railway self-dumping vehicle which the axes of rotation of the bottom doors are disposed in the longitudinal direction of the vehicle.

Fig. 1 is a cross sectional view of the self-dumping vehicle ready for loading, and 30 Fig. 2 a similar view showing the vehicle in the discharged state.

The two bottom doors B are connected, so as to allow of swinging motion, with respect to the stationary under frame A of the 35 vehicle by means of bearings a^1 disposed to either side of the central longitudinal plane. The said doors are arranged at an incline, their lower edges bearing against each other in the central longitudinal plane of the 40 vehicle, they thus meeting to form a funnel-shaped loading space, while their upper edges are provided with bearings b^2 , by means of which they are pivotally connected with the side members or walls C of the 45 vehicle. Each of these latter is in turn articulated at the ends of its upper edge, facing the stationary end walls A^2 of the vehicle, by means of a hinge c^1 with the end of a guide link D adapted to rotate about a pivot 50 a^3 fixed in the said end wall A^2 . When the vehicle is ready for loading, the two bottom doors B are interconnected at their lower edges b^1 by intervention of any convenient simple locking device one embodi-

ment of which is shown in the drawing. It 55 comprises the latch e pivoted at d to one of the doors B and adapted to engage a pin f rigidly fixed on the opposing door.

The bearings a^1 are disposed relatively to the bottom doors B suchwise that when the 60 vehicle is loaded and the locking device released, the bottom doors will automatically open outward in consequence of the effect exerted by the weight of the load.

It will thus be readily understood that 65 when the vehicle is to be discharged of its contents, the locking device, which secures the bottom doors, is first of all released, whereupon these doors being opened downwards by the weight of the lading by rotating 70 around the axes of bearings a^1 , the said doors lifting at the same time the side walls C which are articulated to their upper edges, and causing said side walls to swing inwardly in the direction indicated by the arrows x in Fig. 1, the walls assuming then 75 the position shown in Fig. 2. This position causes a large discharge opening to be formed between the bottom doors, these latter and said side walls now being disposed 80 in practically one and the same plane, that is, in approximate parallelism, which again 85 yields a steep chute, so that lading materials possessing even a great power of cohesion and adhesion may be reliably and quickly discharged. The discharging operation is moreover additionally facilitated by the fact that, owing to the sudden change in the configuration of the cross sectional area of the vehicle, the material to be discharged is 90 suitably broken up and loosened.

The discharge having been effected, the 95 movable parts of the vehicle automatically return into the initial position as shown in Fig. 1, and this occurs either and solely by the effect of their own proper weight, or else by the intervention of spring means or counter weights, whereupon the bottom doors are once more interconnected at b^1 by means of the locking device.

I claim:

1. In an automatic self-dumping vehicle, a bottom portion comprising two doors swingingly mounted on the vehicle frame and adapted to open centrally and automatically by the weight of the lading, and side walls movably connected to the upper edges of the said doors, so that each of the 100 105

side walls is swung into approximate parallelism with its connected door in the course of its motion.

2. In an automatic self-dumping vehicle, 5 a bottom portion comprising doors swingingly mounted on the vehicle frame and adapted to open centrally and automatically by the weight of the lading, stationary end walls, and side walls articulated at their 10 lower edges to the said doors and connected at their upper edges to guide links rotatably mounted on the said end walls.

3. In an automatic self-dumping vehicle, 15 a bottom portion comprising doors swingingly mounted on the vehicle frame and adapted to open centrally and automatically by the weight of the lading, stationary end walls, and side walls articulated at their lower edges to the said doors and connected 20 at their upper edges to guide links rotatably

mounted on the said end walls, and arranged transversely to the axes of rotation of the said doors.

4. In an automatic self-dumping vehicle 25 a bottom portion comprising two doors swingingly mounted on the vehicle frame and adapted to open centrally and automatically by the weight of the lading, and side walls movably connected to the upper edges of the said doors, so that each of the 30 side walls is moved conjointly with its connected door in the course of its motion.

The foregoing specification signed at Essen, Germany, this 6th day of September, 1920.

FRITZ FINCKH.
